UNITED STATES PATENT OFFICE.

RAYMOND R. TRACY, OF MORRISON, ILLINOIS.

EGG-CASE.

1,198,792.

Specification of Letters Patent. Patented Sept. 19, 1916.

Application filed October 21, 1915. Serial No. 57,139.

To all whom it may concern:

Be it known that I, RAYMOND R. TRACY, a citizen of the United States, residing at Morrison, in the county of Whiteside and 5 State of Illinois, have invented certain new and useful Improvements in Egg-Cases, of which the following is a specification.

This invention relates to cases for shipping and transporting eggs and has as its 10 object to provide a case of this class especially designed to receive and protect eggs contained within an ordinary egg carton disposed within the case and has as one aim to so construct the case as to effectually 15 protect the eggs from becoming broken or cracked while being shipped or transported.

Another aim of the invention is to so construct the case that the side walls of the 20 carton will be spaced from the corresponding side walls of the case so that blows or pressure received by the side walls of the case will not be transmitted to the eggs in such manner as to result in their breakage.

25 Another aim of the invention is to so construct the case that it may be repeatedly used and will be substantial although so light in weight as not to add materially to the cost of transportation.

30 Another aim of the invention is to provide means for closing the case which means will serve effectually to prevent accidental opening of the case and loss of its contents and yet may be readily manipulated to permit of inspection of the contents by postal authorities.

In the accompanying drawings: Figure 1 is a perspective view of the device embodying the present invention closed and ready 40 for transportation. Fig. 2 is a similar view illustrating the case opened and the egg carton partly withdrawn. Fig. 3 is a vertical longitudinal sectional view through the device, the egg carton being shown in elevation. Fig. 4 is a perspective view of the inner section of the case. Fig. 5 is a vertical transverse sectional view through the case and the carton housed therein. Fig. 6 is a perspective view of the carton open.

50 The egg case embodying the present invention includes an open ended outer section or case and an intermediate skeleton section or spacing member within which latter is disposed the inner section or carton containing the eggs to be transported. The outer section comprises side walls 1, a

top wall 2, and a bottom wall 3, the said section being open at both ends as clearly shown in Fig. 3 of the drawings. The outer section of the case and in fact the 60 case as a whole is preferably oblong so as to adapt it to receive the ordinary oblong egg carton, although it may assume any desired shape depending, of course, upon the shape and size of the carton which it is intended to receive.

The intermediate or spacing section of the egg case embodying the present invention as well as the outer section of the said case is preferably formed from strawboard and the said intermediate section is folded up from a blank cut from this material or such other material suitable for the purpose as may be employed, and comprises a bottom 70 4, a top 5, a connecting end 6, and an end 7. The lateral edge portions of the bottom 4 are folded up to form flanges 8 and the corresponding edge portions of the top 5 are folded to form flanges 9, the lateral or vertical edge portions of the end 6 being folded 75 to form flanges 10 and the edge portions of the blank constituting the edge portions of the said walls are cut or slit as indicated at 11 so that the ends of the flanges 8 and 9 adjacent the end 6 of the said section will 80 practically meet the ends of the flanges 10 at the corresponding sides of the said section. When folded in the manner illustrated in Fig. 4 of the drawings, the intermediate section of the case is designed to be 85 slidably fitted within the outer section thereof in the position shown in Figs. 3 and 5 of the drawings and with the sections thus 90 assembled, the end wall 6 of the intermediate section closes one end of the outer section. The end 7 of the intermediate section is designed to be swung at its line of juncture with the bottom wall 4 of the intermediate section to open and closed positions and in order that this member of the intermediate section may be reinforced at its said 95 line of juncture with the bottom wall 4, a cloth or tape binding 12 is secured to the under side of the bottom wall 4 and the outer side of the end wall 7 along the said line of juncture between these parts. When 100 the sections have been properly assembled the inner section or egg carton to be housed within the case and of the form, for example, shown in Fig. 6 of the drawings and indicated in general by the numeral 13, after having been filled with eggs is slid- 105 110

ably fitted within the intermediate section of the case and the end 7 may then be swung to closed position and secured in a manner to be presently described.

- 5 Referring now to Figs. 2 and 5 of the drawings, it will be observed that when the egg carton is properly positioned within the intermediate section of the case embodying the present invention it will be housed between the walls 4 and 5 of the intermediate section and will rest at one end against the wall 6 of the said section and will be spaced by the flanges 8, 9 and 10, from the side walls 1 of the outer section of the case.
- 10 Also, when the end wall 7 is swung to closed position it will rest against the other end of the egg carton and will serve effectually to close the case at its end opposite the end which is closed by the wall 6.
- 15 In order that the end wall 7 of the intermediate section of the case may be held closed as shown in Figs. 1 and 3 of the drawings, a disk 14 is riveted or otherwise secured to the outer face of the said end wall, and passed about the shank of the rivet, which rivet is indicated at 15, is one end portion of a tying cord 16, the end of the cord being tied to form an open knot 17 through which the cord is threaded after
- 20 having been passed about the said shank of the rivet 15. A metallic disk 18 is disposed against the upper surface of the top wall 2 of the outer section of the case near that end at which the end wall 7 of the intermediate section is located when the sections are assembled, and disposed upon the disk 18 is a disk 19 of any suitable friction material, the disks being secured together and to the said top wall 2 by a rivet 20. The
- 25 upper surface of the disk 18 is preferably convex and the disk 19 is preferably substantially flat so that when the cord 16 is passed between the disks 18 and 19 and about the shank of the rivet 20 and is pulled
- 30 taut it will be securely held against slipping and in this manner the end wall 7 is held closed.

In order that the ends of the flanges 8 and 9 may be prevented from becoming mutilated or spread in such manner as to interfere with the ready insertion of the egg container, small staples or other suitable stiffening elements, indicated at 21, are secured in vertical position through the outer ends of the said flanges thereby compressing the layers between which the corrugated intermediate layer of the material from which the intermediate section is formed, is located, so as to reduce the thickness of the flanges at their said ends.

It will be understood that while from the foregoing description of the invention the walls 2 and 3 of the outer section are described as constituting the upper and lower walls of these sections and the walls 4 and

5 of the intermediate section are described as constituting the upper and lower walls of the said intermediate section, the sides 1 of the outer section may constitute the bottom and top of the said section and the walls 70 4 and 5 of the intermediate section may constitute the sides of the said intermediate section.

Having thus described the invention, what is claimed as new is:

1. A mailing case including an outer section open at one end, a container disposed within the outer section, and an intermediate spacing section interposed between the outer section and the container and including 80 spaced walls provided with inwardly projecting marginal flanges bearing against adjacent walls of the outer section and container respectively.

2. A mailing case including an outer open 85 ended section, a container disposed within the outer section, and an intermediate spacing section interposed between the outer section and the container and including spaced upper and lower walls provided with inwardly projecting flanges the longitudinal edges of which are spaced apart, said flanges contacting with the adjacent walls of the outer section and container respectively.

3. A mailing case including an outer section open at both ends, a container fitted within the outer section, and a removable intermediate spacing section interposed between the outer section and the container and including oppositely located walls and 100 a hinged end wall, the first-mentioned walls being designed to rest against corresponding walls of the outer section when the sections are assembled and the hinged wall when swung laterally being designed to close one 105 end of the case as a whole, means for closing the other end of the case, and flanges formed upon said spaced walls of the intermediate section and bearing against the outer section and container respectively for spacing 110 the container from the outer section.

4. A mailing case including an outer open ended section, a container fitting within the outer section, an intermediate spacing section interposed between the outer section 115 and the container and provided with spaced inwardly projecting flanges adapted to bear against the outer wall of the container and the inner wall of the outer section respectively, and stiffening members piercing the 120 flanges.

5. A mailing case including an outer open ended section, a container fitted within the outer section, an intermediate spacing section interposed between the outer section 125 and the container and including upper and lower walls connected by an integral end wall, the opposite longitudinal edges of the upper and lower walls of the spacing member being bent inwardly to form spaced

- flanges adapted to contact with the container and outer section respectively, a hinged end wall forming a part of the intermediate spacing section and adapted to extend over 5 the container and close one end of the outer section when swung upwardly to closed position, and stiffening members piercing the flanges of the intermediate section near the hinged wall thereof.
- 10 6. A mailing case including an open ended outer section, a container fitting within the outer section, an intermediate skeleton spacing section interposed between the outer section and the container and including 15 spaced upper and lower walls connected at one end by an integral end wall, there being a second end wall hingedly connected to the bottom wall, flanges projecting inwardly from the top and bottom walls and the integral end wall of the spacing section and 20 adapted to bear against the outer wall of the container and the inner wall of the outer section respectively, and a securing element fastened to the hinged wall of the intermediate section and engaging the outer 25 section near one end thereof for preventing withdrawal of both the container and intermediate spacing section.

In testimony whereof, I affix my signature.
RAYMOND R. TRACY. [L. S.]
